US0D1073009S

(12) **United States Design Patent** (10) **Patent No.:** **US D1,073,009 S**
(45) **Date of Patent:** **** Apr. 29, 2025**

(54) **GAS CONTAINER**

(71) Applicant: **Hexagon Ragasco AS**, Raufoss (NO)
(72) Inventor: **Andreas Birger Lørum**, Raufoss (NO)
(**) Term: **15 Years**
(21) Appl. No.: **35/520,220**
(22) Filed: **Mar. 5, 2023**
(80) **Hague Agreement Data**

Int. Filing Date: **Mar. 5, 2023**

Int. Reg. No.: **DM/227623**

Int. Reg. Date: **Mar. 5, 2023**

Int. Reg. Pub. Date: **Mar. 8, 2024**

Primary Examiner — Keli L Hill

(57) **CLAIM**

The ornamental design for a gas container as shown and described.

DESCRIPTION

1. Gas container
2. Gas container
3. Gas container
- 1.1 : Perspective
- 1.2 : Front
- 1.3 : Back
- 1.4 : Left
- 1.5 : Right
- 1.6 : Top
- 2.1 : Perspective
- 2.2 : Front
- 2.3 : Back
- 2.4 : Left
- 2.5 : Right
- 2.6 : Top
- 3.1 : Perspective
- 3.2 : Front
- 3.3 : Back
- 3.4 : Left
- 3.5 : Right
- 3.6 : Top

Ornamental designs for gas containers.

1 Claim, 18 Drawing Sheets
